LOCKING MECHANISM

Kenly C. Bugg, Fort Wayne, Ind.

Application November 20, 1939, Serial No. 305,278

16 Claims. (Cl. 70—68)

This invention pertains to locking mechanism, and more particularly to a lock for a hookless fastener or Zipper.

It is an object of this invention to provide a combination lock for a hookless fastener.

Another object is to provide a lock for a hookless fastener which is small, secure, and inexpensive to manufacture.

Still another object is to provide a combination lock for a hookless fastener which is adapted to provide means for readily operating the latching means of a hookless fastener, and which can be readily applied to existing fasteners as well as to fasteners made for this purpose.

15 A further object is to provide a combination lock for a hookless fastener which is secure and strong, yet may be encased in a plastic or other decorative casing without decreasing the security or strength.

20 With these and various other objects in view, the invention may consist of certain novel features of construction and operation as will be more fully described and particularly pointed out in the specification, drawing and claims appended hereto.

In the drawing, which illustrates embodiments of the device and wherein like reference characters are used to designate like parts—

Figure 1 is a top plan view of a portion of a hookless fastener showing a lock embodying the invention applied thereto;

Figure 2 is an enlarged side elevation of a hookless fastener slide showing a combination lock embodying the invention applied thereto;

35 Figure 3 is an enlarged transverse sectional elevation through one form of combination lock embodying the invention showing the same applied to the slide of a hookless fastener;

Figure 4 is an enlarged sectional plan taken substantially in the plane as indicated by the line 4—4 of Figure 3;

Figure 5 is an enlarged sectional plan taken substantially in the plane as indicated by the line 5—5 of Figure 3;

45 Figure 6 is an enlarged sectional plan taken substantially in the plane as indicated by the line 6—6 of Figure 3;

Figure 7 is a perspective elevation of one of the locking members provided in the combination lock illustrated in Figure 3;

50 Figure 8 is an enlarged sectional elevation of a modified form of combination lock embodying the invention, showing the same applied to the slide of a hookless fastener;

55 Figure 9 is an enlarged sectional elevation of another modified form of combination lock embodying the invention, showing the same applied to the slide of a hookless fastener;

Figure 10 is an enlarged sectional elevation of 60 still another modified form of combination lock

embodimenting the invention, showing the same applied to the slide of a hookless fastener;

Figure 11 is an enlarged sectional elevation of yet another modified form of combination lock embodying the invention, showing the same applied to the slide of a hookless fastener;

Figure 12 is a transverse sectional elevation through a modified form of maze adapted for use in the combination locks embodying the invention.

Hookless fastener

In the combination locks illustrated herein, as applied to a hookless fastener, it is of course understood that the same form of hookless fastener and slide therefor are provided for each of the modifications illustrated. The hookless fastener 20 is shown as applied to the fabric or base 22, the interlocking fastening means thereof being of the well known Zipper type and adapted to be 20 locked and unlocked by the slide 24 adapted to be moved along the hookless fastener. In the embodiment illustrated, the slide is adapted to be moved toward the right as viewed in Figure 1, to open the fastener, and moved toward the left 25 as viewed in said figure to close said fastener, the slide being the conventional slide, including the upper member 26 and the lower member 28, said members being adapted to embrace the fastening means of the hookless fastener 20, the upper and lower members being spaced apart and joined at the flared end 30 by the centrally disposed web 32.

Lock shown in Figures 3 to 7, inclusive

Referring first of all more particularly to the form of combination lock illustrated in Figures 3 to 7, inclusive, as applied to the slide 24, said lock includes the base 34 suitably secured as at 36 to the top of said slide, said base being provided with the upwardly extending cylindrical portion 38 forming a lower seat 40 for the expansion spring 44. The spring is adapted to embrace the central post 46 which extends upwardly and is internally threaded as at 48. The upper end of the spring is seated on the disk 50 apertured as at 52 for sliding cooperation with the post 46. Said disk is provided with the depending locking pin 54 adapted to extend downwardly for reciprocation in the registering apertures 56 and 58 provided in the base 34, and the upper member 26 of the slide, the spring normally urging the pin upwardly out of its locking position between the adjacent fastening members of the hookless fastener 20, it being understood that when the pin is disposed between adjacent hooks the slide cannot be moved.

The rotating operating member 60 is provided to rotate around the post 46, said operating member including the outer casing 62 extending down-

wardly to embrace and be journaled on the cylindrical portion 38, said member being rotatable with respect to the disk 50, and being provided with the apertured plain track member 64, the periphery of the aperture forming a bearing on the post 46 and being provided with the spaced cut-out portions 66 for receiving one of the control members, all as later described. Above the track member 64 the post is provided with the cut-out portion 68 for receiving the ball or control member 69, said ball being disposed between the plain track member 64 and the stationary maze member 70, said maze member being secured to the post as by the key 72, the maze being retained in position by means of the shoulder 74 provided on the post and the assembly screw 76 received in the threaded portion 48 of the post. The maze may be recessed as at 78 for the reception of a decorative closure cap 80, and the outer periphery of said maze may form a bearing for the casing 62. The maze member 70 is similar to that shown and described in Patent No. 2,116,011, granted May 3, 1938, to Kenly C. Bugg, and also application Serial No. 205,648 filed May 2, 1938, being provided with the track portions 82 extending inwardly of the plain or directing track 84, the plain track member 64 serving as actuating means to direct the ball 69 inwardly in accordance with the selected combination on the maze 70 until the ball is moved into the cut-out portion 68.

Operation

Assuming the ball to be in the position where it is disposed between the plain track member 64 and the maze 70, it forms a means for locking the pin 54 in engagement between adjacent fastening members of the hookless fastener. Thus the slide is locked as the pin 54 is projected downwardly. In order to unlock the slide, the member 62 is depressed slightly toward the slide 24. This causes the ball 69 to move outwardly against the inside of the member 62, it being understood that the lock is held in another than vertical position. The member 62 may then be rotated in accordance with the combination, the combination being counted by the clicks, in the form illustrated, until it is received in the cut-out portion 68. Slight additional rotation of the member 62 will cause one of the members 66 of the plain track member to register with the ball, at which time the spring 44 will propel the locking member 50 and the member 62 upwardly, trapping the ball and causing the pin 54 to be moved out of its position between adjacent hooks of the fastener. The slide can then be moved to open or close the fastener, as the case may be, and after it is moved to its desired position the member 62 may be depressed to project the pin 54 into locking position, which movement releases the ball 70 from the registering apertures 68 and 66, whereupon it becomes necessary to repeat the operation above described to reopen the lock for operation of the hookless fastener.

Lock shown in Figure 8

In the embodiment of the lock illustrated in Figure 8, the base member 86 is suitably secured to the upper member 26 of the slide 24, the base member 86 being provided with the aperture 88 registering with an aperture 90 provided in the upper member 26. The base member is provided with the cylindrical portion 92 forming a lower seat 94 for the conical spring 96, the upper part 76 of the spring 96 being provided with the depend-

ing portion 98 forming a locking pin for engaging between the adjacent fastening members of the hookless fastener. The upper end of the spring is seated against the under side of the rotatable plain track member 100, similar to the track member 64, said track member being carried by the rotatable cylindrical casing 102, the track member being apertured as at 104 for the reception of the center post 106 of the base member 86. The center post is provided with the head 108 for securing the stationary maze member 110 thereto, said maze member being similar to the maze member 70. The ball 112 is disposed between the members 110 and 100, and the post 106 is apertured as at 114 for reception of the ball 112 after it has been moved in a predetermined manner by rotation of the member 102. The outer periphery of the member 110, as well as that of the member 92, and the inner periphery of the member 100, form bearings for the member 102, and the member 102 may be conveniently closed by means of the cap 116.

Lock shown in Figure 9

In the modification illustrated in Figure 9, the flanged base member 118 is secured to the upper member 26 of the slide 24 and is provided with the aperture 120 registering with the aperture 122 of the member 26. The base member is also provided with the center post 124 to which the closure cap 126 is secured, as between the shoulder 128 and the enlarged head 130 of said post, the closure member 126 conveniently being used as the maze member, and the outer periphery thereof forming a bearing of the rotatable operating sleeve 132. Said sleeve 132 is provided with the plain track member 134 journaled as at 136 to the post, the ball 138 being disposed between the members 134 and 126, and being adapted to be moved in a predetermined manner as determined by the maze, into the aperture 140. The conical spring 142 is seated on the base member 118 at one end, and its upper end on the under side of the track member 134, being provided with the depending locking portion 144 adapted to extend through the apertures 120 and 122, and moved into locking position between the adjacent fastening members of the fastener.

Lock shown in Figure 10

In the construction illustrated in Figure 10, the base member 146 of the lock may be suitably secured to the upper member 26 of the slide 24, the base member being provided with the aperture 148 registering with the aperture 150 in said slide. The base member 146 is provided with the upstanding flange 152 forming a bearing for the rotatable operating sleeve 154. The sleeve 154 is provided with the plain track member 156 adapted to be rotated by the sleeve 154 and journaled as at 158 on the stationary sleeve or post 160. The stationary cap 162 is suitably secured to the sleeve 160 by means of the rivet 164 which preferably extends through the closure member 162, the sleeve 160, the base 146, and the upper member 26 of the slide, and forms fastening means between the lock and slide 24. The member 162 may conveniently take the form of the maze member for the ball 166 disposed between the members 162 and 156, said ball being adapted to be operated, in the manner determined by the maze, into the aperture 168 provided in the sleeve 160. A conical spring 170 is disposed between the members 156 and 146, and is provided with the depending locking portion 75

172 extending through the apertures 148 and 150 where it may be projected into locking position on the hookless fastener.

Lock shown in Figure 11

5 In the construction illustrated in Figure 11, the base member 174 may be suitable secured to the upper member 26 of the slide 24 and is provided with the aperture 178 registering with the aperture 178 of the upper member 26. The base member 174 is provided with the upwardly extending flange 180 forming a bearing for the rotatable operating sleeve 182. The sleeve 182 is provided with the plain track member 184 journaled as at 186 to the centrally disposed post 188. In the construction shown the post 188 is provided with the rivet portion 190 extending through the base member 188 and the upper member 26 of the slide, forming fastening means therewith, and the post 188 is provided with the closure portion 192 which may also form the maze member for the ball 194. The post 188 is provided with the depressed portion or aperture 196 for the reception of the ball 194, said ball being moved to said aperture in a manner determined by the maze. The conical spring 188 is disposed between the members 184 and 174 and is provided with a depending locking portion 200 extending through the apertures 178 and 178.

30 *Operation of locks shown in Figures 8 to 11, inclusive*

35 In the operation of the devices illustrated in Figures 8 to 11, inclusive, the operation is similar to that already described with respect to the lock illustrated in Figure 3; that is, in order to zeroize the lock the sleeves 102, 132, 154 and 182 are moved toward the slide, causing the balls 40 to move out of the slots 114, 148, 168 and 196. The sleeves can then be rotated in accordance with the combination determined by the mazes until it is received in the respective slots, at which 45 the springs cause the sleeves to move away from the slide, permitting the pins 98, 144, 172 and 200 to be moved out of locking position between the adjacent fastening members of the hookless fastener. The slide can then be moved to the position desired, and the sleeves can be depressed toward the slide to cause the balls to 50 move out of the respective slots, and to project the pins into locking position, being held in locking position by the separation between the plain track member and the maze member carried 55 by the disposition of the balls therebetween.

Maze shown in Figure 12

60 In the construction shown in Figure 12, a maze 202 is provided wherein the face of the maze is substantially conical, such as shown in Reissue Patent No. 21,320, granted January 16, 1940, or of course it may be of some other shape, such as spherical, so that the slide need not be tipped out of vertical position. When these types 65 of mazes are used, of course the plain track members must be similarly (complementarily) constructed. Further, while the maze has been described as being stationary, it is of course understood that the maze may be rotatable, that 70 is, the positions of the plain track member and the maze member may be reversed and the maze member is then rotated by the operating sleeve.

75 It is to be understood that I do not wish to be limited by the exact embodiments of the device shown, which are merely by way of illus-

tration and not limitation, as various and other forms of the device will of course be apparent to those skilled in the art without departing from the spirit of the invention or the scope of the claims.

What is claimed is:

1. In a lock, the combination of a stationary member having a spring seat, locking means including a projection extending through said stationary member, a spring interposed between said means and said seat, a rotatable operating member, a plain track member, a maze member, one of said last named members being adapted to be rotated by said operating member, a ball disposed between said members and movable in accordance with said maze member, and means for receiving said ball for permitting said spring to move said projection to inoperative position.

2. In a lock, the combination of a stationary member having a spring seat, locking means including a member forming a spring seat, a locking projection on said second named member, an expansion spring disposed between said seats, a rotatable operating member having a plain track member, said operating member being rotatable and slidable with relation to said stationary member, a stationary track member having a maze thereon, said stationary track member being secured to said first named stationary member, a ball disposed between said track members and movable to inoperative position to permit movement of said locking projection to inoperative position.

3. In a combination lock adapted to be applied to a slide for a hookless fastener, means adapted to be moved by said lock into and out of locking position, said lock including a rotatable operating member, said rotatable operating member being adapted to be rotatably mounted on said slide but fixed against dissociation therefrom, means for urging said first named means to inoperative position, and means controlled by predetermined movements of said operating member for permitting movement of said first named member to operative or inoperative position.

4. In a lock, the combination of a base member having an outer peripheral flange and a centrally disposed post, a rotatable operating member encircling said flange, a track member carried by said operating member and extending radially toward said post, a spring disposed between said base member and track member and urging said track member away from said base member, a stationary track member secured to said post and extending radially toward said operating member, one of said track members having a maze thereon, a ball disposed between said track members and movable toward said post by predetermined rotating movements of said operating member in accordance with said maze, said post having an aperture for receiving said ball for permitting movement of said first named track member toward said second named track member, said spring having a projection extending through said base member, said projection being in one position when said ball is between said track members and in another position when said ball is in said aperture.

5. In a lock, the combination of a base member having an outer peripheral flange and a centrally disposed post, a rotatable operating member encircling said flange, a track member carried by said operating member and extend-

- ing radially toward said post, a spring disposed between said base member and track member and urging said track member away from said base member, a stationary track member secured to said post and extending radially toward said operating member, one of said track members having a maze thereon, a ball disposed between said track members and movable toward said post by predetermined rotating movements of said operating member in accordance with said maze, said post having an aperture for receiving said ball for permitting movement of said first named track member toward said second named track member, said spring having a projection extending through said base member, said projection being in one position when said ball is between said track members and in another position when said ball is in said aperture, and a closure member carried by said operating member extending over said post.
6. In a lock, the combination of a base member having an outer peripheral flange, a rotatable operating member encircling said flange, a track member carried by said operating member and extending radially toward said post, a spring disposed between said base member and track member and urging said track member away from said base member, a stationary track member extending radially toward said operating member, one of said track members having a maze thereon, a post extending between said stationary track member and said base member and fastened thereto, a ball disposed between said track members and movable toward said post by predetermined rotating movements of said operating member in accordance with said maze, said post having an aperture for receiving said ball for permitting movement of said first named track member toward said second named track member, said spring having a projection extending through said base member, said projection being in one position when said ball is between said track members and in another position when said ball is in said aperture.
7. In a lock, the combination of a base member having an outer peripheral flange, a rotatable operating member encircling said flange, a track member carried by said operating member and extending radially toward said post, a spring disposed between said base member and track member and urging said track member away from said base member, a stationary track member extending radially toward said operating member, one of said track members having a maze thereon, a post extending between said stationary track member and said base member, fastening means extending through said second named track member, said post and said base member, a ball disposed between said track members and movable toward said post by predetermined rotating movements of said operating member in accordance with said maze, said post having an aperture for receiving said ball for permitting movement of said first named track member toward said second named track member, said spring having a projection extending through said base member, said projection being in one position when said ball is between said track members and in another position when said ball is in said aperture.
8. In a lock, the combination of a base member having an outer peripheral flange, a rotatable operating member encircling said flange, a track member carried by said operating member and extending radially toward said post, a spring disposed between said base member and track member and urging said track member away from said base member, a stationary track member extending radially toward said operating member, one of said track members having a maze thereon, a post extending between said stationary track member and said base member, fastening means extending through said second named track member, said post and said base member, a ball disposed between said track members and movable toward said post by predetermined rotating movements of said operating member in accordance with said maze, said post having an aperture for receiving said ball for permitting movement of said first named track member toward said second named track member, said spring having a projection extending through said base member, said projection being in one position when said ball is between said track members and in another position when said ball is in said aperture.
9. In a lock, the combination of a base member having an outer peripheral flange, a rotatable operating member encircling said flange, a track member carried by said operating member and extending radially toward said post, a spring disposed between said base member and track member and urging said track member away from said base member, a stationary track member extending radially toward said operating member, one of said track members having a maze thereon, a post extending between said stationary track member and said base member, fastening means provided on said post and extending through said base member, a ball disposed between said track members and movable toward said post by predetermined rotating movements of said operating member in accordance with said maze, said post having an aperture for receiving said ball for permitting movement of said first named track member toward said second named track member, said spring having a projection extending through said base member, said projection being in one position when said ball is between said track members and in another position when said ball is in said aperture.
10. A lock according to claim 1 wherein the ball engaging surfaces of the track and maze members are angularly disposed with respect to the axes of the operating member.
11. A lock according to claim 4 wherein the ball engaging surfaces of the track members are substantially frusto-conical.
12. A lock according to claim 5 wherein the ball engaging surfaces of the track members are substantially frusto-conical.
13. A lock according to claim 6 wherein the ball engaging surfaces of the track members are substantially frusto-conical.
14. A lock according to claim 7 wherein the ball engaging surfaces of the track members are substantially frusto-conical.
15. A lock according to claim 8 wherein the ball engaging surfaces of the track members are substantially frusto-conical.
16. A lock according to claim 9 wherein the ball engaging surfaces of the track members are substantially frusto-conical.

KENLY C. BUGG.
